UNITED STATES PATENT OFFICE.

JOSEPH HALE, OF SOMERVILLE, ASSIGNOR TO JOSEPH N. HALE, OF BELMONT, MASSACHUSETTS.

IMPROVEMENT IN MACHINES FOR COILING, CONDENSING, AND SHAPING FIBROUS MATERIAL.

Specification forming part of Letters Patent No. 147,769, dated February 24, 1874; application filed February 14, 1874.

To all whom it may concern:

Be it known that I, JOSEPH HALE, of Somerville, in the county of Middlesex and State of Massachusetts, have invented an Improvement in Coiling, Condensing, and Shaping Fibrous Material; and I do hereby declare that the following, taken in connection with the drawings which accompany and form part of this specification, is a description of my invention sufficient to enable those skilled in the art to practice it.

The invention relates to a machine for forming fibrous material—more especially jute and similar raw material—into a coil, and compressing the material and compacting the coils together, and shaping the compacted or condensed coil.

In the construction of my machine, I make a cylinder or shell mounted so as to rotate upon a central shaft, and having an interior surface shaped to the form to be imparted to the outer surface of the coil, and the shaft I make as a sleeve, having at one end a head-plate clamped to it, against which head the coil is formed and compressed, and at its opposite end a gear driven by suitable connection with the motive power that operates the machine. Through this sleeve a screw-shaft passes, said shaft working in a screw-thread formed in a suitable nut, that stands against a stationary bearing in which the rear end of the shaft-sleeve turns, the screw-shaft having a rotative movement in common with the sleeve, and a feed or longitudinal movement within the sleeve, and the head being attached to the screw-shaft by a pin that extends through a slot in the sleeve, the groove permitting the head to slide or move forward or back with the screw-shaft, and the head rotating with the sleeve and screw-shaft.

When the machine is rotated, the screw-shaft and head are slid back, so as to leave only space enough between the head and the stationary wall at the rear end of the rotary shell for entrance of the ends of the fibers to be coiled and compressed, the fibers entering through a suitable throat adjacent to the end plate of the shell. The tubular shaft or sleeve being then rotated until the fibers begin to wind and hold upon the shaft, the nut is stopped,

and the continued rotation of the shaft will then draw in the material as fast as it is presented, and will wind it upon the sleeve, filling the shell and imparting to the coil the shape of the inner walls of the shell, the screw-shaft and head being fed forward by the rotation, and the coil gaining in length as the head progresses, the coils being compacted against the head and together, and the compression being increased at any time, if necessary or desirable, by releasing the nut and permitting the screw-shaft to rotate, and the fibers to accumulate upon the sleeve without forward movement. It is in this means for coiling and compacting fibrous material and shaping the compacted coil that my invention consists.

The drawing represents the machine for coiling and compacting fibrous material, and shaping the compacted coils.

Figure 1 shows a plan of the machine. Fig. 2 is a front view of it. Fig. 3 is a sectional elevation.

a denotes the base; *b*, an upright or stand, in which and in a bearing, *c*, a tubular shaft or sleeve, *d*, is journaled. The stand *b* is made with an annular bearing or ring, *e*, in which is supported the rear part of a hollow cylinder or shell, *f*, the end of said cylinder abutting against a shoulder, *g*, and the front of the cylinder having a flange, *i*, the face of which rests and rotates against friction-rollers *h*. The tubular shaft extends axially through this cylinder, and has upon its front part a head or plate, *k*, which slides upon the shaft, but rotates with it, a screw-pin, *l*, extending through the hub of the plate, and through a slot, *m*, in the shaft *d*, and into a screw-shaft, *n*. The shaft *d* may be driven by means of a bevel-gear, *o*, meshing into and driven by a bevel-gear, *p*, on a shaft, *q*, such shaft *q* being driven by any suitable geared connection. Into or through the shaft *d* extends the screw-shaft *n*, which shaft can slide freely in the shaft *d*, but has upon it, outside of the bearing *c*, and resting against the end of the shaft *d*, a nut, *r*, from which extends an arm, *s*, the nut, if held stationary, effecting the forward progression of the screw, (when the shaft *d* is turned in the proper direction,) the shaft *d* and screw *n* rotating without progression of the screw-shaft, if the nut is permitted to ro-

tate with the shaft. To hold the nut stationary, a stop, *t*, is used, against which stop the arm *s* strikes, and is held when the shaft is turned, the nut and arm rotating if this stop is moved from the path of movement of the arm.

The inner surface of the cylinder or shell *f* is shown as shaped quadrangularly, (and it may be made of any other suitable form,) and into one side of the cylinder or shell leads a throat, *u*, through which the material to be coiled, compressed, and shaped, is introduced, there being over this throat within the shell a shoulder, *v*, forming the end of a scroll-face, *w*, by which the entering material is guided to the shaft *d*, upon which it is to be wound. The head-plate *k* is or may be shaped to correspond with the interior of the shell, and extending from its inner face, are pins *x*, against which the fibers catch and hold as they commence to wind. Grooves may also be formed in the face of the head for a similar purpose. The head has a tongue or tenon that enters the groove *m*, and enables the head to slide upon the shaft *d* when necessary.

The operation of the machine is as follows: The nut *r*, being turned back upon the screw-shaft, said shaft is slid forward to enable the head-plate *k* to be fastened to the screw-shaft by the pin *l*. Then the head-plate and screw-shaft are pressed back until the head-plate or a pin, *x*, strikes the shoulder *v*, (leaving between it and the face of the scroll a space, into which the fibers can enter through the throat *u*, and wind upon the sleeve *d*,) and the nut *r* is turned back until it strikes the end of the sleeve *d*. The ends of the fibrous material to be coiled are then thrust through the throat and the shaft *d* is turned, the nut *r* being allowed to turn with it, and then by the rotation of the shaft and the presentation of the fibers to it, the fibers will catch against the head and wind upon the shaft, being permitted to thus wind until the fibers are compacted upon the shaft *d*, and fill the space between the head

and the face of the scroll. The stop *t* is then brought into position for the arm *s* of the nut, to be arrested by it, and the rotation of the shaft being continued and the presentation of the fibers kept up, the screw-shaft and its head will move slowly forward, the fibers will be coiled and compacted upon the sleeve, and the coil will be shaped to correspond to the inner surface of the shell.

By these means a very close, compact, and hard coil will be made, the density of which may be increased or regulated by regulating the forward movement of the head *k*, stopping such movement, and thereby increasing the condensation of the coils behind the head, whenever desirable so to do.

When the initial end of the coil fills the shell behind the head-plate, the shell will rotate with the head-plate, and when the plate passes beyond the shell or cylinder, the rotation of the cylinder will be kept up by the coil, the surface of the cylinder shaping such coil, so long as the shaft *d* is rotated and fibers are presented to it through the throat *u*.

I claim—

The combination of the hollow cylinder or shell *f*, the throat *u*, the rotary tubular shaft *d*, the head-plate *k*, the screw-shaft *n*, and the nut *r*, operating to coil and compact fibers or fibrous material, substantially as described.

2. The loosely-rotating shell or cylinder *f*, in combination with the rotating shaft *d*, head-plate *k*, and screw-shaft *n*, substantially as described.

3. The shell or cylinder *f*, formed with a shaping inner surface, combined with the ring *e* and its throat *u*, substantially as described.

4. A stop, *t*, in combination with the nut *r*, screw-shaft *n*, and the head, substantially as described.

JOSEPH HALE.
